UNITED STATES PATENT OFFICE.

BENJAMIN FRANKLIN NIGHTLINGER, SR., OF DULUTH, MINNESOTA.

WRENCH.

1,412,702.

Specification of Letters Patent. Patented Apr. 11, 1923.

Application filed July 7, 1919, Serial No. 308,928. Renewed February 28, 1922. Serial No. 539,908.

To all whom it may concern:

Be it known that I, BENJAMIN F. NIGHTLINGER, Sr., a citizen of the United States, and a resident of Duluth, in the county of 5 Saint Louis and State of Minnesota, have invented certain new and useful Improvements in Wrenches, of which the following is a specification.

This invention is an improvement in 10 wrenches and has reference more particularly to a pipe wrench in which a handle, having a rigid jaw member at one end is provided with a movable outer jaw member pivotally connected therewith.

15 An object of the invention is to provide a pipe wrench in which few parts are used and which shall be simple, cheap and efficient in operation and permit its use with various sizes of pipes, rods, etc., within 20 reasonable limits, without changing the relative arrangement of the necessary parts.

With these and other objects in view, the invention consists in certain features of construction, arrangement and combination 25 of parts as will be hereinafter described and pointed out in the claims, reference being had to the accompanying drawing forming a part hereof, and in which:—

Figure 1 is a side elevation of the 30 proved wrench, as in use,

Figure 2 is a similar view as used with a smaller pipe,

Figure 3 is a side elevation showing the movable jaw as about to be applied,

35 Figure 4 is a perspective view of the front end of the stationary jaw,

Figure 5 is a side elevation of the movable jaw detached.

Referring more particularly to the drawings in Figures 1, 2 and 3, A represents the 40 lever handle of suitable length having adjacent its upper end the spaced apart cheeks α which are located at each side of a circular socket α' as indicated by dotted lines in Figure 1; the cheeks α are pierced in alignment to receive a screw bolt α^2 , which is passed through said cheeks α and the circular tongue β of a hook-shaped jaw B, which will be later described, and held in 45 place by a nut α^3 . Beyond the cheeks α , the lever handle has an extended portion A', the inner edge of which is slightly curved and has the teeth or serrations α^2 extending across such curved portion.

50 55 The movable jaw member B is hook-

shaped, one arm of which is provided with the reduced circular tongue β , which as hereinbefore set forth fits in socket α' of the lever handle A and is held rotatably therein by the screw bolt α^2 . The shank B' of 60 the hook member has its inner face on a curve, such face being preferably smooth up to the point α where it meets angularly the inner serrated face of the nose B² of the hook member, which inner serrated face 65 is also on a curve.

The outer curved edge of the hook member may be brought down to a webbed or spinal back in order to brace the back and to keep it from springing when pressure 70 is placed on the lever or handle, and otherwise to give extra strength in the back of the hook member.

The movable jaw member is made hook-shaped, as shown in Figure 1. The jaws 75 are centered on the top line of the handle A. The inside of the shank B' of the hook member is curved, permitting the pipe, rod, etc., to fall within the line of pull, as shown by the line 1—2. The serrated or toothed 80 surface of the nose B² of the hook member, as shown by the arc 5—6, is so constructed that the surface makes a false circle to the center point of α^2 . The construction and arrangement of the parts as indicated above 85 causes the movable jaw to draw over the pipe instead of hopping off when pressure is put on the handle, thus giving it an instantaneous grip. The relative arrangement of the stationary jaw is so designed 90 that the movable jaw falls over the end of it, and any pressure put upon the handle causes the stationary jaw to run under the pipe P while the movable jaw pulls to and over it.

95 It will be noted that there are three points of contact with the pipe so that it is gripped with even pressure and can be readily turned by swinging the handle to the left, and that it will be so firmly held that it cannot slip 100 within the space between the movable and the stationary jaw.

The wrench should be made of steel, and may be drop-forged or made under a press, and the stationary jaw is preferably made 105 heavier and fuller at the bottom of the front end as indicated by A³.

I claim:—

A wrench as herein set forth consisting 110 of a lever handle member having a slightly

curved rigid jaw member at its outer end, the upper surface of said jaw being serrated, the points of the teeth thereof projecting forwardly; a circular socket within the handle at the inner extremity of said serrated portion, spaced and perforated cheeks enclosing said socket, a hook-shaped movable jaw member comprising a shank having a reduced tongue at one end pivotally held within said socket the pivotal point being upon the top line of the handle member, and a nose at the opposite end, the inner face of the shank being smooth and struck on a relatively flat arc, the inner face of the

nose also struck on a slight arc, said last 15 named arc intersecting the arc of the smooth inner face of the shank angularly and having serrations on said arc, pivotal means connecting the movable jaw with the lever handle on the top line of the handle, whereby the arc of movement of the movable jaw itself and the curvature of the inner serrated face of the nose thereof will describe different intersecting circles, the point of such intersection coinciding with the point of 20 25 intersection of the serrated nose portion and the smooth inner shank portion.

BENJAMIN FRANKLIN NIGHTLINGER, Sr.
